UNITED STATES PATENT OFFICE.

AXEL A. STROM, OF CHICAGO, ILLINOIS.

RATCHET-DRILL.

SPECIFICATION forming part of Letters Patent No. 331,341, dated December 1, 1885.

Application filed February 11, 1884. Serial No. 120,654. (No model.)

To all whom it may concern:

Be it known that I, AXEL A. STROM, a citizen of the United States, residing at Chicago, in the county of Cook and State of Illinois, 5 have invented a new and useful Self-Feeding Ratchet-Drill, of which the following is a specification.

My invention relates to improvements in ratchet-drills, for whatever purpose used; but 10 I have had more particularly in view the drilling of rails when laid upon the track and fastened to the ties.

Figure 1 is a plan view of the entire machine; Fig. 2, a side view; Fig. 3, an end 15 view; Fig. 4, a section along the line xx ; Fig. 5, a plan view of the drill-stock; Fig. 6, an end view, same as Fig. 4; Fig. 7, a plan view of plate in handle covering ratchet; Fig. 8, a 20 sectional view of ratchet, showing dogs and spring; Fig. 9, details of the automatic feed.

Similar letters refer to similar parts throughout the several views.

The frame A A A may be made of several pieces of metal fastened together; but for 25 greater strength I prefer to make it of one piece of bar-iron. It is so constructed as to pass over the rail and catch the rail at or near the center of the web, as shown in Fig. 2. The frame may be made of cast, wrought, or malleable iron, or steel. To the frame is welded or fastened the boss a. The handle or actuating-lever E terminates in a band embracing the drill-stock, as shown in the accompanying drawings. The band in which the actuating-lever terminates contains the plate Fig. 35 7, fastened in its place by screws or pins. In the plate Fig. 7 may be one or more slots, e' , to allow the dogs g to pass in when inserting the drill-stock. Inside the band which terminates the actuating-lever E is slipped the ratchet-wheel e , as shown in Fig. 8. Inserted 40 in the drill-stock are one or more dogs, g , and back of each dog is a spring, g' . I have usually employed two dogs, with a single spring 45 between, as shown in Fig. 8. The ratchet-wheel e is fastened to the band terminating the handle with screws or pins through the holes h , so as to be easily removable. The nut G, screwed upon the drill-stock, prevents 50 it from slipping out of the band terminating

the handle; or the feed-drum may be so constructed as to accomplish this object.

The automatic feed is accomplished by means of the following mechanism: Attached to the frame, by rivets or otherwise, is a device consisting of one or more jaws, b , a lever, B, and dog B', and pivoted to the lever B is a latch, b' . The lever B and dog B' are made in one piece, which is hinged in the jaws b . The cog-wheel C is attached to the feed-screw c , 55 which screws into a female screw in the drill-stock D. Upon the drill-stock is fastened the hollow cylinder or feed-drum D', which has one side cut out in the manner shown in the drawings. 60

By the term "drill-stock" is comprehended the device for holding the head of an ordinary drill, and which passes through the band and terminates in a cylinder, on the inner side of which is cut the female screw, as above set 65 forth. 7c

The operation of the automatic feed is as follows: When the lever B is upon the unbroken surface of the feed-drum D', the dog B' does not catch in the cog-wheel C, and 75 the drill-stock D does not feed on the feed-screw c ; but when the lever B falls upon the side d of the feed-wheel, cut out as described, the dog B' catches in the cog-wheel C, and the drill-stock feeds on the feed-screw—that is, 80 in the first case both the drill-stock D and the feed-screw c turn together, while in the latter case the dog B' holds the cog-wheel C, and with it the feed-screw c , stationary, and the drill-stock D, revolving upon the feed-screw c , 85 is advanced toward the rail.

The design of the feed-drum D, in combination with the lever B, the dog B', and the cog-wheel C, attached to the feed-screw c , is to cause the drill to be advanced toward the 90 rail as rapidly as it is drilled away, and yet not so rapidly as to make the operation of the drill difficult, if not impossible, as would be the case were the feed continuous.

When the drill is first placed in position, the 95 latch b' is turned out, thereby causing the dog B' to hold the cog-wheel C. This causes a continuous turning of the drill-stock upon the feed-screw, and a continuous advancement of the drill toward or against the rail. When 100

the drill begins to bite the rail, the latch is thrown under the lever by the operator, and the action of the self-regulating automatic feed begins, as above set forth.

5 I am aware that the use of the ratchet-drill for the purpose of drilling rails is well known; but I do not know of any automatic or self-feeding ratchet-drill used for drilling rails, and in my invention the arrangement of the 10 ratchet entirely protected from sand and gravel, and with the pins upon the drill-stock, and the ratchet arranged as described, so as to be easily removable, is, as I believe, new, as well as the application of an automatic or self-feeding device to a ratchet track drill, and the 15 frame passing over the rail and not requiring a wedge or lever to fasten or hold it.

What I claim as new, and desire to secure by Letters Patent, is as follows:

20 1. The frame A A A, made to pass over the rail and catch the rail at or near the center of the web, substantially as described.

25 2. The ratchet e, with one or more dogs g, spring g' back of each dog, and the slots e' e' in the plate Fig. 7, to allow the dogs to pass in, all substantially as described.

3. The combination of the dog B', lever B, and latch b' with the feed-wheel D', substantially as described.

4. The combination of the dog B' and lever 30 B with the feed-drum D', substantially as described.

5. The self-feeding device consisting of a lever, B, and dog B', a feed-drum, D', cog-wheel C, and feed-screw e, attached to a ratchet-drill, substantially as described. 35

6. In combination with a ratchet-drill, the dog B', lever B, latch b', and feed-wheel D'.

7. The combination, as described and shown, of the frame A, drill-stock D, and actuating-lever E, with the self-feeding device, substantially as described. 40

8. The combination, as described and shown, of the frame A, drill-stock D, and actuating-lever E, with the self-feeding device and the 45 ratchet e, substantially as described.

9. The machine consisting of the frame A, boss a, jaws b, lever B, dog B', latch b', cog-wheel C, feed-screw e, drill-stock D, feed-wheel D', actuating-lever E, plate Fig. 7, 50 ratchet e, slots e' e', dogs g g, spring g', and nut G, substantially as described.
